UNITED STATES PATENT OFFICE.

WILLIAM H. HARMON, OF CHICAGO, ILLINOIS.

GAS-STOVE.

1,072,115.

Specification of Letters Patent.

Patented Sept. 2, 1913.

Application filed March 23, 1912. Serial No. 685,778.

To all whom it may concern:

Be it known that I, WILLIAM H. HARMON, a citizen of the United States, and a resident of the city of Chicago, county of Cook, and State of Illinois, have invented 5 certain new and useful Improvements in Gas-Stoves, of which the following is a specification.

My invention relates to improvements in 10 gas stoves and has for its object the provision of a gas stove provided with means for increasing the heating efficiency thereof.

The invention consists in the combinations 15 and arrangements of parts hereinafter described and claimed.

The invention will be best understood by reference to the accompanying drawing forming a part of this specification, and in which—

20 Figure 1 is a perspective view of a gas stove equipped with means embodying my invention, Fig. 2, an enlarged section through the top of the stove above a burner, Fig. 3, a perspective view of a housing 25 employed in the construction, Fig. 4, a perspective view of a modified form of housing shown in inverted position, Fig. 5 is a vertical section taken upon the line 5—5 of Fig. 4, and Fig. 6 is a detail 30 perspective view of one of the burners illustrated in Fig. 1, parts being broken away.

The form of construction illustrated in Figs. 1, 2 and 3 of the drawing comprises a downwardly tapering sheet metal housing 1 adapted to fit over and rest upon a burner 2 of the stove. Housing 1 is provided at its upper edge with notches 3 adapted to receive the usual supporting fingers 4 of the stove and at its lower 35 edge with notches 5 adapted to admit air to facilitate combustion. By this arrangement the heat and flame from a burner will be confined and concentrated against the bottom of the cooking utensil, and thus the heating efficiency thereof increased.

In the form of construction shown in Fig. 4 a cylindrical housing 6 is provided having notches 7 in its upper edge adapted to receive the supporting fingers 4 of the

stove, and notches 8 in its lower edge 50 adapted to admit air as before. A supporting flange 9 is secured to the lower edge of housing 6 by means of tongues 10 thereon which are passed through slots in said flange and bent over against the bottom of the flange as shown in Fig. 2. In this construction the flange 9 is designed to rest upon the burner and the notches 7 to receive the supporting fingers as before. By extending flange 9 both inwardly and 60 outwardly, a broad supporting surface is presented and a secure fastening afforded for tongues 10. The action of this form of housing is the same as before, this form being provided to fit a different style of 65 burner.

While I have illustrated and described the preferred forms of construction for carrying my invention into effect, these are capable of variation and modification without departing from the spirit of the invention, I, therefore, do not wish to be limited to the precise details of construction set forth, but desire to avail myself of such variations and modifications as come within the scope 75 of the appended claims.

Having described my invention what I claim as new and desire to secure by Letters Patent is:

1. The combination with a gas stove 80 burner, of a housing positioned over the burner and arranged to confine the flame against the bottom of a cooking utensil, said housing being provided with notches at its upper edge adapted to receive the utensil 85 supporting fingers of the stove, said notches being larger than said fingers to afford ventilation; and with notches at its lower edge adapted to admit air, substantially as described. 90

2. The combination with a gas stove burner, of a cylindrical housing positioned over the burner and arranged to confine the flame against the bottom of a cooking utensil, said housing being provided with 95 notches at its upper edge adapted to receive the utensil supporting fingers of the stove and with notches at its lower edge

adapted to admit air, said upper notches being larger than said fingers to afford ventilation; and a supporting flange secured to the lower edge of said housing and projecting inwardly and outwardly therefrom and resting upon said burner, substantially as described.

In testimony whereof I have signed my name to this specification in the presence of two subscribing witnesses.

WILLIAM H. HARMON.

Witnesses:

ARTHUR A. OLSON,
JOSHUA R. H. POTTS.
